UNITED STATES PATENT OFFICE.

WILLIAM C. HUNTOON, OF PROVIDENCE, RHODE ISLAND.

COLLAPSIBLE TUBE.

1,313,189.

Specification of Letters Patent. Patented Aug. 12, 1919.

Application filed March 26, 1919. Serial No. 285,256.

To all whom it may concern:

Be it known that I, WILLIAM C. HUNTOON, of Providence, in the county of Providence and State of Rhode Island, have invented a new and useful Improvement in Collapsible Tubes, of which the following is a specification.

This invention relates to certain new and useful improvements in a collapsible tube, commonly used for containing tooth paste, shaving cream, paint, etc., and more particularly to the manner of connecting or attaching the closure cap thereto.

The principal object of the invention relates in the formation or mounting of the hinge knuckles on the tubes to which the hinge, that carries the closure cap, is pivoted.

A further and equally important object is to provide means for hingedly connecting the closure cap to the tube to prevent loss or mislaying of the cap, said means having a swivel connection with the cap, so that the latter may readily be rotated to engage its threads with those on the tube.

Further objects will appear as the description progresses and those features on which protection is desired will be succinctly defined in the claims.

In the drawings—

Figure 1 is an elevation of the upper portion of a collapsible tube embodying the present invention in its preferred form.

Fig. 2 is a horizontal section therethrough on line 2—2 of Fig. 1.

Fig. 3 is a similar view through a modified form of the invention depicting a pair of hinge knuckles.

Fig. 4 is a view similar to Fig. 1 of a further modified form of the invention and showing the closure cap swung open on its hinge mounting, and

Fig. 5 is a top plan view thereof.

Referring more in detail to the drawing, the numeral 1 designates the collapsible tube having the cap 2 threaded on the discharge end 3 in the usual manner by continued screw threads, or the discharge end may have an interrupted thread 4, as depicted in Figs. 4 and 5, which provides two diametrically opposite lugs having their lower edges inclined downwardly for engagement by a pair of diametrically opposed lugs 5 extending inwardly from the side wall of the cap 6.

The closure cap is formed with a polygonal perimeter to be grasped in applying or

removing the cap from the tube body, and underlying this gripping portion the cap is formed with an annular groove 7 in which engage the sides of an elongated loop 8. 60 This loop is formed from a single length of wire bent into U form and having its arms brought together for a short distance, as at 9, and then deflected outwardly and again inturned to provide opposed trunnions 10. 65 These trunnions are adapted to be sprung apart to receive the hinge knuckle 11 therebetween and enter a bearing opening 12 extending through the knuckle. The cap is thus adapted to turn freely in its confining 70 loop 8 to engage and disengage the threads of the discharge end or nozzle of the tube, the loop riding on the cap or in the groove during such lengthwise movement of the cap on the tube. The outturned portions 13 constitute shoulders for engaging the knuckle and limiting the swinging movement of the wire hinge.

The formation of the hinge knuckle comprises a very important part of this invention since it is practically impossible to solder a knuckle on the tube owing to the quality of the metal from which these tubes are made. To this end the knuckle is formed integral with the tube and this 80 knuckle may be formed in this direct manner by any one of several methods employed in forming the tubes. Furthermore, the knuckle may be formed in two parts, i. e., the tube may have a pair of knuckles formed 85 integral therewith.

This latter form of the invention is depicted in Fig. 3 wherein the pair of knuckles 14 have bearings 15 to receive the outturned ends 16 of the hinge member which as in 95 the former instance, comprises a loop 8 and a contracted portion 9, the outturned ends 16 being carried directly on said portion 9.

The cap is securely attached to the tube without in any manner interfering with the 100 free and easy turning of the cap incidental to the removal and replacement of the same from and on the tube. The annoyance of looking for the cap after using the tube is obviated; the construction is simple and 105 inexpensive; and the sanitary conditions about the mouth of the tube are capable of easy maintenance.

Having thus described my invention, what I claim as new and desire to secure by Letters Patent is—

1. A collapsible tube composed of a cylin-

2
drical body having an end closing wall of somewhat conical shape and a neck extending out from the center of the end closing wall, a closure for the neck, a transversely 5 perforated hinge knuckle formed integral with said end closing wall and located in spaced relation to the neck, and a wire loop loosely connected to the base of the cap so as to allow said cap to freely rotate, the ends 10 of the loop being sprung into the knuckle perforation.

2. A collapsible tube composed of a body having an integral end closing wall, a neck extending out from said wall, a closure cap

for the neck, a perforated hinge knuckle 15 formed integral with the end closing wall in the forming of the tube and extending upwardly therefrom and means to connect the cap to the knuckle including a bail rotatably encircling the cap and having its ends engaged in the perforation of the knuckle. 20

In testimony whereof I have signed my name to this specification in the presence of two subscribing witnesses.

WILLIAM C. HUNTOON.

Witnesses.
